GEORGE C. THOMAS, JR., OF ELIZABETH, NEW JERSEY, ASSIGNOR TO THE THOMAS & BETTS CO., OF ELIZABETH, NEW JERSEY, A CORPORATION OF NEW JERSEY.

CABLE CONNECTER.

Application filed July 11, 1925. Serial No. 42,888.

This invention relates to improved cable connectors for fastening a cable in an electrical fixture box.

An object of the invention is to produce a connector which is partially severed longitudinally to permit the armored cable entry or receiving end to expand and anchor itself in a box hole, while the other end, the end which remains normal in size, carries a full one-piece continuous circular wire bushing.

My connector is improved in respect to a full type bushing which is carried at the hinged ends of a number of expandible sleeve portions or sections and which bushing acts as a stop against which the armor of the cable rests and through which the insulated cable wires pass, and said full type bushing is made in combination with a split sleeve integrally formed and pivotal upon and at the full type circular bushing. Furthermore, my improvements enable the connector to be made from a single piece of sheet metal despite the fact that the sleeve is split to make it expandible at one end and despite the fact that a full uncut, unbroken, unsplit circular bushing is integrally formed with the split sleeve.

Split sleeve connectors are well known in the art and so are bushings which are also split, but I combine a split sleeve with an unsplit bushing and accomplish certain improved and efficient results in the assembly of a box, a cable, and connector not possible with split bushings. I have designed and constructed a full circular bushing because it does not wear or abrade and damage the rubber insulation covered wires drawn therethrough such as may occur with split bushings, and I utilize the split sleeve because it expands and effectively locks or anchors itself in a box hole.

Simplicity in one piece structure, economy in production, and a single operating means for simultaneously fastening a cable in the connector and anchoring the connector in a box are accomplished in this improved connector.

The accompanying drawing illustrates a preferred form of the invention wherein:

Figure 1 shows a top view of an ordinary electric outlet fixture box in fragmentary section and in which the connector is insert-

ed prior to being expanded therein to anchor it in the box, and this view shows the sleeve 55 connector in longitudinal section.

Figure 2 shows an outside end view of the connector in a box as taken on the section line 2-2 thereby showing a connector and cable anchored in position.

Figure 3 shows an assembly view in section as taken on the line 3-3 of Figure 2.

Figure 4 shows a modified form of the cable connector by which the clamping screw 65 may be mounted on the outside of the box instead of on the inside thereof.

Figures 5 and 6 show side and front end views of the connector removed from the box.

Electric wiring installation work ordinarily requires electrical fixture boxes B ordinarily having knockouts thus providing box holes H into which a connector and a cable C are inserted, and it is an object to produce an inexpensive type of a single 75 piece sheet metal connector which may if desired have a single operating means to carry out the expanding of a connector in the box hole and clamping a cable in the 80 connector with the wires W from the armor 80 C of the cable passing through the connector to the inside of the box.

The connector embodies a full and complete circular bushing 10 made integrally at one end on two or more parallel half 85 round sleeve sections 11 and 12. A slot 13 cuts through the front end of the sleeve, but stops short of the rear end thereof to leave sufficient stock at the bushing 10 by which the connector parts 11 and 12 remain 90 intact. In fact two parallel oppositely disposed longitudinal slots 13 extend through and from the front end 14 of the connector back to the full type bushing 10 where the slots 13 stop before cutting too far into the 95 rear end of the connector although the slots may cut slightly into the bushing but terminate short of reaching too far therearound where a raw edge of the slot would cut and damage the rubber insulation on the wires 100 passing therethrough. The result of this arrangement is to form bending zones 9 at the rear end of the connector adjacent or in the bushing 10 whereby the two half sleeve sections 11 and 12 may easily expand or move 105 apart at the front end 14.

The front expandible end 14 of the connector is provided with suitable means, such as a groove 16, for anchoring the connector in the box hole H when the parts 11 and 12 are expanded. This groove registers with the rim of the box hole H and securely anchors the connector in the box. Any other suitable means may be adapted as anchorage means.

10 Clamp means such as a screw 15 is mounted in one of the sections 11 or 12 and is adapted to screw down against the armor of the cable C which causes the sections 11 and 12 to expand thereby tightly bringing the 15 grooves 16 or other means outwardly against the box edge H and at the same time the screw 15 anchors the cable C in the connector sleeve because the screw bears down on the cable C.

20 The modified form of connector shown in Figure 4 similarly consists of sleeve sections 20 and 21 separated by splits 23 with a bushing 22 similar to that already described, and the splits enable the parts 20 and 21 to 25 be forced apart or expanded by a simultaneously acting cable clamp and sleeve expanding means, as the screw 25. A bending zone 28 exists at the end of each split 23 by which the two sleeve sections remain integrally and hingedly intact.

An extension piece 24 is made on the outer end of the expandible sleeve parts 20 or 21 and the screw 25 is carried in this extension. The screw 25 is adapted to bear against a 35 cable when inserted in the connector and the screw acts to simultaneously anchor the cable in the connector and expand the connector groove 26 against the box wall H. An additional screw hole 27 may be made in the connector sleeve so that the screw 25 may for convenience be used either inside or outside the box B.

The cable clamp and connector expanding screw 25 performs several useful functions, 45 not only in the form of the invention shown in the first figures, but in the modified structure shown in Figure 4 as well. However, the screw 25 in Figure 4 may be used either outside the box or placed in the screw hole 27 50 within the box, and in either case the screw functions to expand the connector and lock it in the box hole H and simultaneously anchor the cable in the sleeve.

The assembly view Figure 3 shows the end 55 of the armor C of the cable resting directly against the cable stop bushing 10 with the rubber insulation covered wires W passing through the round oval aperture defined by the full circulation bushing 10. The armor C of the cable is in no way damaged by the splits 13 or 22 which separates the sleeve in spreading sections, but the splits are terminated prior to reaching the round oval aperture formed through the bushing 60 in order that no damage occur to the wires

W. It is a marked advantage to produce a single piece cable connector split longitudinally and the two or more parts of which are integrally hinged at a bending zone yet not impair the utility of the device by splitting the bushing.

The groove 16 or 26 constituting the connector anchorage means by which the connector is anchored or locked in the box hole is merely exemplary of one suitable means 75 employed for this purpose. Also the single clamp or operating means comprising screw 15 or 25 not only anchors the cable C inside the sleeve connector but simultaneously expands the connector half-sections until the 80 anchoring groove becomes effective against the rim of the box hole H. The connector is made of sheet metal and may be drawn or fashioned either from a tube or flat stock material having a bending zone 15 embraced 85 at or within the area of the bushing 10 enabling the half-sections to readily spread apart under force of the screw.

What I claim is:

1. A cable connector comprising a sleeve 90 with an open end to receive cable and a restricted end to stop the cable armor, said sleeve provided with slits which extend through the cable receiving end but which terminate short of cutting through the restricted end of the sleeve, said slits being provided to partially separate the sleeve into parts which expand at one end and which remains normal in size at the other end thereof, a malleable metal bending zone 100 formed at the end of the slit terminating at the normal size end of the sleeve which enables the other end to expand, connector anchorage means carried on the expandible end by which the sleeve is anchored in a box, 105 and means carried by the connector adapted to clamp against a cable inserted in the sleeve and adapted to simultaneously expand the expandible end of the connector thereby making operative the connector and box anchorage means in a box hole.

2. A cable connector comprising a sleeve, 110 said sleeve provided with two oppositely disposed parallel slits cutting the sleeve longitudinally into two separable expandible sections left connected together at one end by a bending zone, said slits cutting through one end of the sleeve but terminating short of cutting through the other end of the sleeve thereby forming a bending zone of metal as 120 aforesaid and thereby leaving the sections connected as aforesaid, a full circular wire bushing fashioned into the sleeve at the bending zone end to protect insulated wiring drawn through the bushing, connector anchorage means carried on the sleeve, and clamp means carried by the sleeve to anchor cable therein and to simultaneously expand the end of the sleeve carrying the connector anchorage means.

3. A cable connecter for anchoring cable in a box comprising, parallel portions circular in cross section composing a cable receiving sleeve, a full circular wire bushing integrally formed at one end of the portions joining all portions together in a one-piece sleeve structure, the bushing acting to constrain one end of the sleeve to normal size and permitting the other end of the sleeve 10 to expand, a connecter and box anchorage means formed in the movable ends of the sleeve portions, and a screw carried by the sleeve to simultaneously expand the movable connecter portions to anchor a cable in the 15 sleeve.
4. A cable connecter for anchoring cable in a box comprising, parallel half-round parts composing a cable receiving sleeve, a full circular wire bushing integrally formed 20 at one end of the half-round parts joining all parts together in a one-piece sleeve structure, the bushing acting to constrain one end of the sleeve to normal size and permitting the other end of the sleeve to expand, a connecter and box anchorage means formed in the movable ends of the sleeve parts, an extension made on one of the sleeve parts, said sleeve part provided with a screw hole in the 25 extension and with a screw hole on the other side of the anchorage groove opposite the

first named screw hole, and a screw adapted for use in either screw hole.

5. A cable connecter for anchoring cable in a box comprising, parallel parts composing a connecter member, a full circular wire 35 bushing integrally formed at one end of the member joining all parts together in a one-piece structure, the bushing acting to constrain one end of the member to normal size and permitting the other end of the member 40 to expand, a connecter and box anchorage groove formed in the expandible ends of the parts, an extension made on one of the parts, said member being provided with a screw hole in the extension, and a screw 45 mounted in the screw hole.

6. A connecter comprising a member fashioned from a sheet metal blank and including a full-fashioned uncut circular wire bushing of fixed size at one end of the member, a number of normally parallel portions formed integral at one end thereof with the bushing which leaves their other ends expansibly free, box hole edge anchorage means carried on the expandible ends of the portions, and clamp means carried with the connecter to grip a cable and simultaneously expand the anchorage means. 50 55

In testimony whereof I affix my signature.

GEORGE C. THOMAS, JR.
